UNITED STATES PATENT OFFICE

RALPH MOLINARI AND JOHN BALDI, OF CHICAGO, ILLINOIS, ASSIGNORS TO SEMINOLE FURNITURE SHOPS, INC., OF CHICAGO, ILLINOIS, A CORPORATION OF ILLINOIS

SLIDE MECHANISM

Application filed April 7, 1928. Serial No. 268,165.

Our invention relates, generally, to extensible tables and more particularly to furniture of this class in which the extension leaves are normally carried by the table and 5 may be pulled out or extended to a position at the end of the table, thereby to form a continuous top of greater area.

We have provided an extensible table top construction which overcomes the main disadvantages in tops of this type wherein the normal top is raised to permit the withdrawal of the extensions. In this latter type of extensible table, the operation of withdrawing and turning the extension leaf is 15 very difficult since the operator must lean over the table to raise the central portion of the top both in withdrawing the extension leaf and in returning it to concealed position. Women, especially, therefore have great difficulty in extending the table and returning it to normal closed position. Furthermore, in this type of table the extension leaf is liable to become scarred and scratched as it is being withdrawn from its closed position 20 and returned thereto. Occasionally, while raising the central portion of the top, it slips from the fingers and is liable to injure the hands of the operator.

The extensible top construction of our invention overcomes all of the above disadvantages and has a great many advantages not present in the extensible tables of the prior art.

More particularly, it is the object of our invention to provide an extension table in 35 which the extension leaves may be easily and quickly withdrawn from beneath the table top and firmly held in extended position.

A further object of our invention is to 40 provide an extensible table in which the extension leaves are guided so as to be movable outwardly, upwardly and then inwardly into position, forming an extension of the table top.

45 A further object is to provide an extensible

table in which the top may be rigidly secured to the table legs or pedestal.

A further object is to provide an extensible table having means for guiding the extension leaves from closed to extended position 56 without danger of scarring the surface of the extension leaf.

Another object is the provision of an extensible table top in which the extensible section is adapted to be automatically moved 55 out from under the table top and automatically leveled therewith, and located immediately adjacent the table top so as to form an extension thereof.

Other objects will appear from the following description, reference being had to the accompanying drawings, in which

Fig. 1 is a plan view of our improved table, the major portion of the fixed top being broken away more clearly to show the operating mechanism of the extension leaves;

Fig. 2 is a longitudinal vertical sectional view of the table taken on the line 2—2 of Fig. 1;

Fig. 3 is a similar view showing the extension leaves in normal or closed position;

Fig. 4 is a perspective view of a guiding lug; and

Figs. 5 to 10 are detailed views of the means for guiding the extension leaves, representing the parts thereof in the different positions assumed at various stages of operation.

As best shown in Figs. 1, 2 and 3, the table of our invention comprises legs 10 which are 58 preferably of the extended pedestal type, the two legs being braced by a cross piece 11. The legs support a frame having sides 12 and ends 13. The ends of a cross member 14 are rigidly secured to the mid-portions of 55 sides 12 in any suitable manner. Sides 12 also support stop boards 15 which are recessed as at 16 to receive the ends of cross member 14. A central stationary top 17 is secured upon the stop boards 15 and cross member 14. 60

The stationary top is thus rigidly held a short distance above the frame. Blocks 19 are rigidly secured between the ends 13 and the legs 10. Each of these blocks 19 carries a guiding mechanism represented generally by the reference character 20. This mechanism will be fully described hereinafter.

The frame ends 13 have guide recesses 21 with bottom bearing surfaces 23 for runners 22, a pair of which is secured to each of the extension leaves 24, the latter being preferably of the same width as the stationary top 17. The extensions have suitable recesses 18 which are adapted to receive the fingers 15 while the extension leaf is being moved to extended position.

The ends of runners 22 are offset at 25 for engagement beneath the cross member 14, as shown in Fig. 2. A lug plate 26 is secured in 20 a recess in the lower surface of each of the runners 22, preferably by screws passing through countersunk holes 27, so that the plates lie flush with the bearing surfaces of the runners. The plates 26 are rectangular 25 in shape and have inwardly extending lugs 28 for engagement with the operating mechanism 20.

The extension leaves 24 are slidable from their normal position between the stationary 30 top 17 and the frame 12, 13, as shown in Fig. 3, to extended positions in which they abut the ends of the stationary top 17 and are flush with the surface thereof as shown in Figs. 1 and 2. We have provided novel mechanism 35 for automatically raising and guiding the extension leaves from their normal to extended position and back to normal position.

This raising and guiding mechanism, which is best shown in Figs. 5 to 10, inclusive, comprises pairs of metal plates 30 which are secured to the outer sides of blocks 19 by 40 screws passing through countersunk holes 32 in the plates. Each of the plates 30 has an outwardly bent end flange 34, the lower portion 36 of which slopes toward the center of the table.

A hardened metal abutment block 38 is 45 fixed against the flange 34. A trip lever 40, a dog 42, and a counterweight lever 44 are mounted for pivotal movement upon the plate 30 by rivets 46, 48 and 50, respectively. Each 50 of the elements 40, 42 and 44, it will be noted, is pivoted eccentrically of its center of gravity and the pivotal mounting is sufficiently 55 frictionless so that the elements will readily swing on their pivots due to the force of gravity alone.

The trip lever 40 has a notch 52 near its outer end, this notch being adapted to receive 60 the point 54 of dog 42. A pin 56, fixed to the plate 30, limits counterclockwise pivotal movement of the trip lever 40 and a similar pin 58 serves as a limit stop for counterclockwise pivotal movement of the dog 42.

The counterweight lever 44 has a toe 60

which, as shown in Fig. 5, normally lies beneath and in contact with the heel portion 62 of the trip lever 40.

In Figs. 5 to 10 we have illustrated the positions of the operative parts of the guiding and raising mechanism at different stages of the operation of moving an extension leaf to extended position and returning it to normal position. These operations will now be described in detail.

In each of these figures, the lug 28 is shown in section. It will be understood that this lug slides substantially in contact with the inner surface of the plate 30 and, since it is rigidly secured to the extension leaf, the movement of the lug may be considered to be the movement of the extension leaf.

Referring to Fig. 5, the lug 28 is shown as having moved past the lever 44 through a rectilinear path *a*. When the lug reaches the position approximately as shown in Fig. 5, the inner edge of the extension leaf 24 will lie beneath the outer edge of the stationary top 17. Continued outward movement of the leaf will cause the lug 28 to contact with and slide upwardly upon the upper surface of dog 42 through a path *b* until the lug reaches a position in which the weight of the extension leaf exerted through the lug will pivot the dog 42 clockwise and permit passage of the lug between the end of the trip lever 40 and the point 54 of the dog. When this occurs, the end of the dog 42 opposite the point 54 contacts with the left-hand portion of the trip lever 40 and swings the latter clockwise to the position shown in Fig. 6 if the lever 40 has not already moved to this position under the influence of gravity. The lever 40 thus acts as a stop to limit the clockwise pivotal movement of the dog 42 so that the lug 28 abuts against the block 38 and rests upon the point 54.

Having reached the limit of outward movement of the extension 24, the operator will push inwardly and thereby move the lug 28 through a path *c* to the position shown in Fig. 7.

The inward movement of the extension leaf is continued so that the lug 28 will move from the position shown in section in Fig. 7 to the position shown in dotted lines in said figure. When the lug is in the dotted line position, the extension leaf is substantially in fully extended position, as shown in Fig. 2, and due to its weight, drops slightly, thereby moving the trip lever 40 counterclockwise until its heel portion is stopped by the pin 56. When in this position, the surface of the extension leaf 24 is brought flush with the surface of the stationary top 17. It will be noted that counterclockwise movement of the trip lever 40 will cause clockwise pivotal movement of the counterweight 44.

As the trip lever 40 is pivoted counterclockwise, the dog 42 will pivot counterclockwise,

due to the force of gravity, until it is arrested by stop pin 58 and its point 54 will latch in the recess 52 in the trip lever 40. The parts will remain in this position until it is desired to restore the extension leaf 24 to normal position.

This restoring movement is commenced by drawing the leaf 24 away from the stationary top 17 a short distance so that the lug 28 will travel through a path represented as *d* in Fig. 8. The lug slides over the trip lever 40 and drops downwardly between the trip lever and the block 38 until it contacts with the sloping portion 36 of the flange 34 by which it is deflected so that the subsequently necessary movement of the top 24 towards the fixed top 17 is initiated.

At the end of path *d*, the lug 28 engages the lower surface of dog 42 and pivots the latter clockwise a sufficient distance to permit the lug to pass beneath the dog in a rectilinear path *e*, as shown in Fig. 9. It should be noted that the lug 28 is guided in the paths *e* and *f* by the engagement of the runners 22 with the bearing surfaces 23.

During the period of the movement of the lug through the path *e*, the point 54 of the dog is temporarily released from its latching engagement with the trip lever 40. The parts remain in the position shown in Fig. 9 during substantially the time while the lug is traveling through the path *f*, shown in Fig. 10, due to the fact that the counterweight lever 44 tends to move the trip lever 40 clockwise and hence prevents the point 54 of the dog from camming the right-hand end of the trip lever upwardly.

Just prior to the time when the lug reaches the position shown in Fig. 10, it contacts with the lower surface of the counterweight lever 44 and swings the latter clockwise to the position shown in Fig. 10, at which time its toe portion 60 is freed from contact with the heel portion 62 of the trip lever 40 so that the latter is free to be cammed counterclockwise by the dog 42 which acts under the influence of gravity.

While the lug is moving through the path *f*, the extension leaf 24 starts sliding beneath the stationary top 17 and this inward movement of the extension 24 is continued until the ends of its runners 22 contact with the opposite frame end 13 and the extension leaf itself abuts against the stop boards 15.

Referring more particularly to Fig. 2, it will be seen that when the extension leaf is in extended position its offset portion 25 will lie beneath the cross member 14 and the leaf will thus be supported by these offset portions of its runners and the two lugs 28 which rest upon the trip levers 40. There is sufficient clearance between the top surface of the extension leaves 24 and the under surface of the stationary top 17 so that there will be no danger of marring or

scratching the finished top surface of the extension leaves as they are being operated.

In the operation of extending the table, it is merely necessary to touch the extension itself and the extending operation may be made to slide sufficiently easy that it is practically effortless and the table may be extended by a child. The mechanism controlling the path of movement of the extension leaf is entirely automatic and is so constituted that the operator need merely pull upon the extension leaf until stopped by engagement of the lugs 28 with the abutment blocks 38. At this time the extension leaf will have been raised substantially to the level of the stationary top 17 and the operator need merely push slightly on the extension leaf to move it to home position in abutment with the edge of the stationary top. If desired, the end edge of the stationary top may be made convex and the abutting edge of the extension leaf concave so that the stationary top will aid slightly in maintaining the extension leaf in flush prolongation with the top 17.

Since the operator need merely grasp the outer edge of the extension, there is no danger of pinching or otherwise injuring the operator's fingers when the extension leaf is moved to extended position. The slope of the top surfaces of the dogs 42 is at such an angle that the raising of the extension leaf is gradual and does not require the exertion of a great force. Furthermore, the engagement of the lugs with the top surfaces of the dogs 42, when moving the extension leaf toward extended position, serves as a signal to the operator that the leaf has moved substantially to its outermost position and thus tends to prevent the use of excessive force which might burr or shear off the lugs by excessive forceful impact with the abutment blocks 38.

While we have shown and described a particular embodiment of our invention in detail, we do not wish our invention to be limited to the particular construction disclosed but desire the scope of our invention to be defined by the claims which follow.

We claim:

1. In an extension top table, guiding mechanism comprising a plate having an abutment, a lever pivoted intermediate its ends on said plate, a dog engaging said lever, and a pin adapted to slide on and be guided by said lever, dog and abutment.

2. In an extension top table, guiding mechanism comprising a supporting plate, a lever carried by said plate and having a notch at one end thereof, a dog on said plate having a tooth engageable with said notch, and a lug adapted to ride over said lever and dog.

3. In an extension top table, guiding mechanism comprising a plate having an abutment, a lever pivoted intermediate its

ends on said plate and having a catch, a dog pivoted intermediate its ends on said plate, and a lug adapted to ride over said lever and said dog and be guided by said abutment.

4. In an extension top table, guide mechanism comprising a plate having an abutment, a lever pivoted intermediate its ends on said plate and having a notch, a dog pivoted intermediate its ends on said plate, said dog being adapted to engage said notch, means to limit the pivotal movement of said lever and dog, a gravity actuated element tending to hold said lever in engagement with said dog, and a lug adapted to be guided by said mechanism.

5. In an extension top blade, guide mechanism comprising a plate having an abutment, a lever pivoted intermediate its ends on said plate and having a latching portion, a dog pivoted intermediate its ends on said plate, said dog being adapted to engage said latching portion, and a lug adapted to ride over said dog and release said latching portion from engagement with said dog.

6. In an extension top table, extension leaf guide mechanism comprising a plate having an abutment, a lever pivoted intermediate its ends on said plate and having a latch, a dog pivoted intermediate its ends on said plate and engageable with said latch lever, and an extension leaf supporting lug adapted to pass over said dog and upon said lever when the leaf is moved to extended position and downwardly between said dog and said abutment and thence beneath said dog when the leaf is returned to normal position.

7. In an extension top table, extension leaf guide mechanism comprising a plate secured to said table, said plate having an abutment at one end thereof, a lever pivoted on said plate and having a latch adjacent one end, a stop for said lever, an extension leaf supporting lug adapted to move in an operating cycle, a dog engageable with said lever and adapted to prevent passage of said lug between said abutment and an end of said dog in one position and to permit said passage when in another position.

8. In an extensible table, the combination of a supporting frame with a top carried by said frame, a movable top section adapted to be supported below said top or as an extension of said top, and a mechanism connecting said movable top section and said frame for guiding the movements of said movable top section and lifting the same to extended position level with said top, said mechanism including a sliding lug carried by one part and a movable member carried by another part for sliding engagement with said lug.

9. In an extensible table, the combination of a supporting frame with a top carried by said frame, a movable top section adapted to be supported below said top or as an extension of said top, and a mechanism connecting said

movable top section and said frame for guiding the movements of said movable top section and lifting the same to extended position level with said top, said mechanism comprising a lug carried by one part and a switch member carried by another part to guide said lug in one path or another dependent on the movement of said movable top section.

In witness whereof, we hereunto subscribe our names this 5th day of April, 1928.

RALPH MOLINARI.
JOHN BALDI.
